DISTILLING APPARATUS

Filed April 12, 1929

UNITED STATES PATENT OFFICE

JAMES McDougall, OF GLASGOW, SCOTLAND

DISTILLING APPARATUS

Application filed April 12, 1929, Serial No. 354,577, and in Great Britain April 18, 1928.

My invention relates to improvements in and connected with distilling apparatus, of what is known as the Coffey type. His apparatus can only deal with liquids which have a small percentage of the desired product. In the case of alcoholic wash this percentage does not come above 5% absolute alcohol (8½% proof). But the wash (hereinafter referred to as the wash) can be fermented economically up to 8% absolute alcohol 12¼ proof, and as the steam required is directly proportional to the quantity of wash distilled, a great saving in steam would be effected if the apparatus could distill the wash of the higher strength without dilution and without loss of spirit. A saving would also be effected in fermenting space for wash and in the time required for distillation.

Coffey's distilling apparatus consists essentially of two vertical columns, the rectifier and the analyzer. The rectifier is divided horizontally into a number of compartments by perforated sheets with coils between. These coils are connected together so that wash entering the top coil passes down through each coil in turn till it passes out of the bottom coil to the top of the analyzer. There are usually about 40 compartments in this column but the number varies slightly.

The analyzer is divided into compartments the same as the rectifier by perforated sheets but has no coils between these, and each perforated sheet has drop pipes to take the wash to the next lower sheet.

Wash is passed down the coils in the rectifier from the topmost coil, passes through all the coils in the column and is then ejected on the top perforated sheet of the column where it meets steam blown into the column in the lowest compartment. The pressure of the steam prevents the wash falling through the perforations and thus the wash runs along the sheet and down the drop tubes to the lower sheet and so on down the whole column where it passes out at a higher temperature (225° F.) after having been denuded of its alcohol vapour by the ascending steam.

This alcohol vapour passes over from the top of the analyzer to the bottom compartment of the rectifier, passes up the column

through the perforated sheets and comes into contact with the coils through which the descending current of wash is passing. The spirit vapour heats this wash and out of the vapour first water and other products with higher boiling points than alcohol are condensed until, at a certain point where the wash in the coils is at temperature of 130°-125° F., the alcohol itself condenses.

The wash passing down the rectifier in the coils gets gradually heated from compartment to compartment until, when leaving the bottom compartment, it has been heated to within a few degrees of the temperature of the incoming spirit vapour and is then run on to the top sheet of the analyzer to meet the upcoming current of steam.

From this it can plainly be seen that there is a balance of heat between the two columns. Any heat taken by the vapour from the analyzer to the rectifier must be taken up by the wash passing through the coils in the rectifier as only a very small proportion of vapour leaves the rectifier in the form of ethers and some non-condensable gases out of the overhead pipe to a worm.

When wash under 5% absolute alcohol content is distilled, the vapour which theoretically should come from the wash has insufficient heat content to heat its wash as it passes up the rectifier so some extra steam is used to make up the deficiency of heat and this is quite evident from the strength of the vapour. By Ure's or Gruening's tables the vapour should be 33.5 U. P. (under proof) from wash containing 4% spirit (7% proof) but in practice we find it nearer 40 U. P. (under proof). At 5% (8½% proof) we find the strength 25 U. P. (under proof) which is what we find on these tables and shows that there is an exact balance between the two columns in the heat content and no extra steam coming over.

It can thus be seen that if more vapour were sent over to the rectifier as would be the case with higher strength of wash, the wash in the coils could not condense this vapour as it, the wash, is already heated up to the temperature of the incoming vapour which is about 180° F. and it can not pass

up the column as the operator will shut off the steam if he sees the temperature rising above the 130° - 125° point. If he allowed it to rise objectional products would come up to this point and spoil the spirit.

As wash at 5% spirit contains 50 gallons absolute alcohol per 1000 gallons, and as this wash at boiling point gives off vapour of 41% strength, the vapour from this will be the vapour of 50 gallons alcohol and 72 gallons water and the temperature of this vapour will be 181° F., and that of the liquor it came from 203° (Ure).

When the strength of the wash is 7% absolute alcohol ($12\frac{1}{4}$ proof) the vapour will be 50% and 1000 gallons wash will give off vapour from 70 gallons alcohol and 70 gallons water, (as against 50 alcohol and 72 water in the former case) so an excess of heat units is apparent in the vapour from the same amount of wash with the higher strength. This vapour (50%) will have a temperature of 180° , and the liquor from which it comes has a temperature of 200.6° F. (Ure) so the same quantity of wash can take up 3° less heat than the weaker wash.

From the foregoing it will be seen that enough heat can not be applied to the wash in the analyzer to vapourize all the spirit in the wash of 7% strength, the result being that this extra spirit runs down the analyzing column with the wash and goes away with the spent liquor.

It will also be seen from the foregoing figures that the wash after leaving the rectifier (where it has done all the condensing) is not up to its own boiling point as its vapour is over 20° lower than the wash from which it came.

My invention resides in the provision of means of distilling the wash of higher spirit strength without loss of spirit and with only a very small increase in the steam required per gallon of wash than is the case when weaker washes are distilled, less than 2% extra steam being required against roughly 50% if wash is distilled at the usual $8\frac{1}{4}$ proof content. As this 2% extra steam is taken up by condensing water in coils the heated water may be returned to the boilers as feed water without loss of heat, all as hereinafter described with reference to the drawing and pointed out in the claims.

In order that my invention may be properly understood and readily carried into effect, I have hereunto appended one sheet of drawing, illustrating my invention, of which:—

Figure 1 is an elevation of apparatus illustrating my invention.

Figure 2 is a plan of Figure 1.

According to my invention, I take the extra heat out of the vapour coming from the analyzer A (which could not be taken up by the incoming wash in the coils L) either be-

fore it reaches the rectifier B by means of coils in an enclosed vessel, where water would circulate, or by a tubular condenser or other means, or, preferably I could have coils C fitted into the lower part D of the rectifier B, as shown, and connect these to an inlet water supply pipe E, the water going into the upper portion of coils C and passing down to the lower section of the coils C leaving the column by the outlet water pipe F. The coils C which I would use for the purpose would do anywhere from the spirit outlet pipe G down to the bottom D of the rectifier B, but preferably one or more of the lowest coils, as shown in Figure 1. On stills which have some extra frames I would disconnect two or more of the frames from the series which make up the wash coils L and circulate water through these, the quantity of water required being easily found by experiment. Theoretically it would amount to 60 gallons of water at 55° heated to 175° for every 1000 gallons of wash of 7% absolute alcohol. (12 $\frac{1}{4}$ proof.)

The pipe O connects the analyzer A with a source of steam, not shown. The pipe P conducts the alcohol vapour from the top portion of the analyzer A to the bottom compartment of the rectifier B.

In addition to the foregoing and as an addition to the invention, I would pass the wash, after leaving the rectifier B where it has been heated as high as possible by the spirit vapour, through the pipe J into a heater I where I would heat it up to at least its boiling point before passing it through the pipe H on to the analyzer A so that less steam would be required to vapourize the alcohol vapour.

This heater takes the form of a pipe coil I contained in a chamber M through which the heating medium passes. In this case the heating medium is the spent liquor coming from the analyzer A through the pipe K and passing it through the chamber M when it would heat the ingoing wash contained in the coils I and then pass out by the pipe N.

It is to be understood that other forms of heater may be employed without deviating from the principle of my invention.

I claim.

1. In a distilling apparatus of the Coffey type for alcoholic wash, comprising an analyzer in communication with a source of steam, a rectifier in communication with said analyzer and having a number of compartments and coils fitted within the lower compartments of the rectifier, means for cooling the vapour coming from the analyzer and extracting the excess heat from spirit vapour.

2. In a distilling apparatus of the Coffey type for alcoholic wash, comprising an analyzer in communication with a source of steam, a rectifier in communication with said analyzer and having a number of compart-

ments, cooling means within the rectifier and communicating means between the lowermost of said compartments and upper part of said analyzer.

3. In a distilling apparatus of the Coffey type for alcoholic wash, an analyzer in communication with a source of steam, a rectifier having a number of compartments above and below an outlet spirit pipe, the lowermost of said compartments being in communication with the upper part of said analyzer, means for heating said alcoholic wash so that less steam will be required to vaporize the alcohol vapours, said heating means comprising a chamber through which the heating medium passes and said chamber connecting one of the lower compartments of the rectifier with the upper portion of the analyzer by means of pipes.
